Inventor:

J. A. Ham

United States Patent Office.

JOHN C. HAM, OF NEW YORK, N. Y.

Design No. 3,448, dated April 13, 1869.

DESIGN FOR A CARRIAGE.

The Schedule referred to in these Letters Patent and making part of the same.

To all whom it may concern:

Be it known that I, JOHN C. HAM, of the city of New York, in the county and State of New York, have invented a new and improved Design for Carriages; and I do hereby declare that the following is a full, clear, and exact description thereof, which will enable others skilled in the art to make and use the same, reference being had to the accompanying drawing, forming part of this specification.

The drawing represents a side elevation of my design.

This invention relates to a new design for the front end of the top of a covered carriage.

The invention consists in arranging on the top of a carriage, of the aforesigned kind, a semicircular glass front, composed of two panes that are adapted to be moved laterally in their frames.

A, in the drawing, represents the body of the carriage.

B is the top.

C, the driver's seat.

The cover D of the carriage reaches over the driver's seat.

The front E of the carriage-top is made of glass in a semicircular form, as indicated, and extends from the height of the seats to the cover, as shown.

Having thus described my invention,

What I claim as new, and desire to secure by Letters Patent, is—

The design for carriages herein described.

JOHN C. HAM.
